UNITED STATES PATENT OFFICE.

WILLIAM J. SCHULTZ, OF CINCINNATI, OHIO.

LOOSE-LEAF BINDER.

No. 813,919.

Specification of Letters Patent.

Patented Feb. 27, 1906.

Application filed September 11, 1905. Serial No. 277,934.

To all whom it may concern:

Be it known that I, WILLIAM J. SCHULTZ, a citizen of the United States, and a resident of Cincinnati, in the county of Hamilton and State of Ohio, have invented a certain new and useful Improvement in Loose-Leaf Binders, of which the following is a description, reference being had to the accompanying drawings, which form a part of my specification.

My invention relates to a device for securing any number of loose leaves in book form and which will permit of leaves being withdrawn or added to from time to time, as occasion requires, the object being to provide a device which will not only be simple in construction, but effective and will firmly hold the desired number of leaves between covers containing my improvement.

The invention consists in providing one cover with a binding post or posts which may be of a determined length or may be of what is known in the art as a "sectional" post, so that the length or size of the posts may be increased from time to time, as desired, the posts receiving the leaves, which are provided with perforations at points registering with the posts and a second cover provided with mechanism whereby this cover is clamped onto the binding or leaf-receiving posts, which mechanism can only be released by the use of a wrench-key, as will be more fully hereinafter set forth.

In the drawings, Figure 1 is a perspective view of a set of covers with my improvement and showing a number of leaves in place, the whole being shown in book form. Fig. 2 is a perspective view of the casing contained in one of the covers in which the clamping mechanism is held with the top plate of the casing removed to show the interior mechanism. Fig. 3 is a sectional view taken on the line 3 3 of Fig. 1 with the key or wrench shown in Fig. 1 withdrawn and a part of the binding or leaf receiving posts shown in full, and Fig. 4 is a sectional view taken on the line 4 4 of Fig. 1.

Like letters of reference indicate identical parts in the respective figures.

A is a cover composed of cardboard or other suitable material, having a suitable binding of leather or canvas or other material used for such purposes, which covering or binding also takes about the casing at the end A' and forms the hinge, as at a, for the cover. The casing B, which is preferably made of sheet metal with the bottom, two sides, and end

walls, as shown in Fig. 2, has secured in it the clamping mechanism, whereby the cover A is retained in place. The clamping mechanism comprises a plate b, whose one end is preferably made in the hooded shape, as at b', (see Fig. 2,) within which hood is preferably placed a block c, having a threaded opening therethrough, which opening registers with openings in the hood b'. The block c is intended to receive the screw d, which screw also takes through the sides of the hood b', its other end being squared to receive the wrench-key C, (see Fig. 1,) which key takes through an opening e in the end of the casing B. The hooded plate b is loosely riveted and secured to the bottom of the casing, as shown at f'. (See Figs. 2 and 3.) It is understood, of course, that the plate b is so riveted or secured to the bottom of the casing B as to permit of slight longitudinal play in the casing, which is accomplished by having a slot in the plate b for the passage of the rivet f, which slot is shown at f'. (See Fig. 3.) This plate b is provided with openings shown at g g, which openings register with similar openings in the casing B. Intermediate of the openings g and secured on top of the hooded plate b within the casing B by rivets or otherwise is a brace-plate h. Secured to the side of the casing B at the point j by a rivet or other suitable connection is the bowed plate or strip of metal k, whose free end lies intermediate of the end of the screw d and the opening g.

D represents a second cover composed of cardboard or other material which is suitably bound with leather or canvas or the like. This cover is provided with the leaf-receiving posts E, secured in the usual manner at the end D' of the cover, and therefore need not be further described. These posts have been illustrated as of the sectional type—that is, each section of the post having one end provided with a threaded stud and its other end provided with a threaded socket to receive the stud on the adjacent section. The top-most section is preferably provided with a rounded end or cap E' to give it a finished appearance. Each section is also preferably provided with openings l. The purpose of the openings l in the different sections of the leaf-receiving posts E is to permit the insertion of a point or other means for screwing or unscrewing the sections, especially after they have become firmly set. In place of a pin or rod to be inserted into the openings l I prefer to construct the key C with

the hooked bifurcated end, as shown in Fig. 1, so that either one of the hooked ends may take into an opening *l* and by reason of the curvature fit around the post *E*, thus providing a wrench for fastening or unscrewing the sections of the post *C*.

B' represents a plate which is provided with openings registering with the openings *g* and is intended to be riveted at the points *m* or in any other way secured on top of the casing *B* to form a top or cover therefor.

The device is employed in the following manner: The leaves *F*, which have perforations at their one end registering with the posts *E*, are placed on the cover *D* by having the posts *E* pass through the perforations, and then the cover *A*, with its clamping mechanism, is placed on top of the leaves, with the posts *E* passing through the openings *g* of the casing *B*, which is secured to the end of the cover *A*. In order to retain this cover *A* in its proper position, the screw *d* is turned by the wrench-key *C*, so as to draw the plate *b* in the direction of the screw, which will bring the wall of the opening in the opposite end of the plate from the hooded portion against the post *E*, while the end of the screw *d* will take through the hooded end *b'* and the block *c*, inclosed therein, and bear against the bowed plate *k*, bringing it into contact with the post *E*, adjacent the plate *k*, and thus form what is known as a "C-clamp."

The reinforcing-plate *h* is secured to the bottom of casing *B* by rivets or pins *h'*, which take through slots in the plate *b*, as can more clearly be seen in Fig. 3. This permits the plate *b* to move independent of the reinforcing-plate *h* when the screw *d* is operated.

I have illustrated and described what I believe to be the preferable construction of my improvement; but of course it will be understood that instead of having the blocks *c* within the hooded end *b'* of the plate *b* the hooded end might be made solid, so as to permit of its being threaded in the opening for the screw *d*. My reason, however, for making the construction as described with a separate block *c* is that this block may be made of material in which a threaded opening is more readily cut, and so at the same time after the threads should become worn it might readily be replaced without the necessity of replacing the entire plate *b*, which of course would necessitate the destruction of the rivets whereby the plate *b* is held in place and having the same riveted anew, and a number of other minor changes might be made without departing from the spirit of my invention.

What I claim as my invention, and wish to secure by Letters Patent, is—

1. A loose-leaf binder comprising a set of covers, the one provided with leaf-receiving posts, the other provided with a casing in its one end having openings registering with said posts, a plate provided with a block at its one

end having a screw-threaded opening therethrough, said plate being adjustably mounted within said casing, said plate adapted to fit about the posts, a threaded rod taking into the threaded opening of said block on said plate and adapted to be controlled from the outside of the casing whereby upon its operation the walls of the openings in said plate are brought into frictional contact with said posts.

2. A loose-leaf binder comprising a set of covers, the one provided with leaf-receiving posts, the second cover provided with a casing in its one end having openings therethrough registering with said posts, an adjustably-mounted plate within said casing provided with openings through which the posts are adapted to take, a plate intermediate of the posts and within said casing, and means adapted to be operated from the outside of said casing whereby the adjustably-mounted plate may be shifted and brought into frictional contact with the posts.

3. A loose-leaf binder comprising a set of covers, one of said covers provided with leaf-receiving posts, a second cover provided with openings adapted to register with the posts, an adjustably-mounted plate within said cover having openings through which said posts take, a reinforcing-plate intermediate of said posts and secured on said adjustable plate, a screw-rod taking into the adjustable plate and adapted to be operated from the outside of the cover whereby upon its operation the walls of the openings in said plate are brought into frictional contact with the leaf-receiving posts.

4. A loose-leaf binder comprising a set of covers, the one provided with leaf-receiving posts, the second cover provided with a casing at its one end having openings registering with the leaf-receiving posts, a plate within said casing provided with openings through which the posts extend, said plate provided with an enlarged end having a screw-threaded opening therethrough, a plate or strip within said casing and intermediate of the post-receiving opening and the screw-threaded openings in the first-mentioned plate and a screw-rod adapted to be operated from the outside of the casing and taking into the screw-threaded opening in said plate whereby the latter is adjusted and the walls of its openings brought into frictional contact with the posts.

5. A loose-leaf binder comprising a set of covers, one of said covers provided with leaf-receiving posts, a second cover provided with a casing in its one end having openings registering with the posts, a plate adjustably mounted within said casing and having openings through which the posts extend, a reinforcing-plate intermediate of the openings in said plate, and means taking through said casing and controllingly connected with said

adjustable plate whereby said plates are brought into frictional contact with the posts.

6. A loose-leaf binder comprising a set of covers, one of said covers having leaf-receiving posts, the second cover provided with a casing in its one end, said casing provided with openings registering with the leaf-receiving posts, a plate adjustably mounted within said casing and having openings 10 through which the posts extend, said plate provided with a hooded end having a threaded opening therethrough, a bowed plate secured within said casing and adapted to extend intermediate of the hooded end of the 15 adjustable plate and the opening therethrough, and means taking through the hooded end of the adjustable plate and bearing against the bowed plate whereby the walls of the openings in the adjustable plate 20 and the hooded plate are brought into frictional contact with the leaf-receiving posts.

7. A loose-leaf binder comprising a set of covers, one of said covers provided with leaf-receiving posts, the other provided with a casing 25 in its one end having openings registering

with said posts, a plate adjustably mounted within said casing and provided with openings through which the posts extend, a screw-rod adapted to take through said casing and into the adjustable plate, and a bowed plate 30 secured within said casing and extending intermediate of the end of the screw-rod and one of said leaf-receiving posts.

8. A loose-leaf binder comprising a set of covers, one of said covers provided with leaf-receiving posts, the other provided with a casing at its one end having openings registering with said posts, a plate adjustably mounted within said casing, and provided with openings through which the posts are 35 adapted to take, a screw-rod adapted to take through said casing and into the adjustable plate, and means secured within said casing and extending intermediate of the end of the screw-rod and one of said leaf-receiving posts. 40 45
